UNITED STATES PATENT OFFICE.

HENRY H. THOMPSON, OF COLUMBUS, GEORGIA.

DRIVING-BOX.

1,220,909.

Specification of Letters Patent.

Patented Mar. 27, 1917.

Application filed September 3, 1915. Serial No. 48,881.

To all whom it may concern:

Be it known that I, HENRY H. THOMPSON, a citizen of the United States, residing at Columbus, in the county of Muscogee and 5 State of Georgia, have invented new and useful Improvements in Driving-Boxes, of which the following is a specification.

This invention has reference to bearing boxes for the driving axles of locomotives, 10 front trucks, trailers and the like, and it may be generally described as an improvement in driving boxes.

The invention has for its object to provide a lateral plate which may be readily detached from the driving box without disassembling or removing the latter, said lateral plate filling the space between the driving box and the face of the driving wheel, the purpose of making the plate readily detachable being to enable the wear surface thereof to be coated with material such as Babbitt metal for the purpose of compensating for wear.

With these and other ends in view which 25 will readily appear as the nature of the invention is better understood, the same consists in the improved construction and novel arrangement and combination of parts which will be hereinafter fully described 30 and particularly pointed out in the claim.

In the accompanying drawing has been illustrated a simple and preferred form of the invention, it being, however, understood that no limitation is necessarily made to 35 the precise structural details therein exhibited, but that changes, alterations and modifications within the scope of the claims may be resorted to when desired.

In the drawing,—

40 Figure 1 is a sectional elevation of a driving box constructed in accordance with the invention, showing also the axle and a part of the wheel.

Fig. 2 is a top plan view of the driving 45 box.

Fig. 3 is a top plan view showing the lateral plate detached.

Fig. 4 is a side view of the driving box with the lateral plate detached.

Fig. 5 is a side view of the lateral plate 50 detached from the box.

Corresponding parts in the several figures are denoted by like characters of reference.

The driving box 15 is in the main of customary construction, being adapted to be 55 mounted in the pedestal, not shown, and being equipped with the brass 16. The face of the driving box is provided with guide flanges 17 which may be dovetailed or otherwise appropriately constructed and which 60 are slightly tapered downwardly for engagement with the lateral plate 18 which is substantially U-shaped as shown, the limbs being provided on their rear faces with grooves 19 adapted to engage the flanges 17. 65

The lateral plate when applied in position for operation, as seen in Fig. 1, straddles the axle and occupies a space between the proximate faces of the driving box and the wheel 20, its purpose being to provide a 70 wear surface and to take up the lateral thrust of the wheel. When the face of the lateral plate becomes worn it may be readily detached by simply tapping the lower ends of the limbs of the plate sufficiently to 75 loosen the same, after which the face of the plate may be coated with Babbitt metal, as indicated at 21, and the plate may then be replaced. Clamping means, such as turn buttons or other appropriate clamp members 80 22, fitted on the screw threaded studs 23 may be used to retain the plate in position and to prevent its being loosened by vibration or other causes.

It will be seen from the foregoing that I 85 have produced an extremely simple and effective means for compensating for wear between the contacting faces of the driving box and the driving wheel, the device being of such a nature as to permit repairs to be 90 very quickly and inexpensively made when needed, all necessity for detaching the driving box or disassembling the same being avoided.

Having thus described the invention, what is claimed as new, is:—

In combination, a driving-box having dovetailed flanges tapered inwardly, a U shaped lateral wear plate; the limbs of which are provided with grooves also tapered inwardly to engage the flanges on the said wear plate, the opposite side of said plate coated with Babbitt metal, said plate 10 having its sides and ends to extend flush

with said driving box, and turn buttons on said box to retain the lateral wear plate in position with respect to the box.

In testimony whereof I affix my signature in presence of two witnesses.

HENRY H. THOMPSON.

Witnesses:

J. A. CURRY,
P. H. CONNELLY.
